NEUTRAL WIRE CLAMPS AND THE LIKE
Norris C. Husted, R.D. 1, Gibsonia, Pa.
Filed June 12, 1959, Ser. No. 820,036
5 Claims. (Cl. 339—149)

This invention relates to a neutral wire clamp and the like and particularly to a supporting clamp providing a ground wire take-off from a neutral conductor.

There has been a great need for a simple wire support or clamp capable of tightly engaging a conductor of various sizes with a provision for taking a ground wire from either side of the support as well as preventing a bolt head in the support from rotation. Various types of cable tap connectors and clamps have been heretofore proposed. They are, however, generally characterized by a multiplicity of separate parts which must be assembled over the cable and the drop wire such as a ground wire. The present invention overcomes this problem and provides a single unitary construction capable of receiving various sizes of conductor and drop wire and, at the same time, preventing the fastener supporting bolt head from rotating.

In a preferred embodiment of this invention, I provide an electrical conductor clamp comprising a generally rectangular member, a transverse slot in said member forming a generally U-shaped opening, a passageway spaced from and parallel to the bottom of said U-shaped opening and adapted to receive a wire, clamp means in the member communicating with said passage to reduce the opening therein for engaging various size wire in said passage in clamping engagement, a reduced portion on one of the legs of said U-shaped member adjacent the passageway creating a zone of resilience whereby one leg of the U-shaped member is free to move toward the other, a passageway through the member transverse to the U-shaped opening adapted to receive a bolt and an abutment means on the member extending to a point adjacent said opening to engage a bolt head to prevent rotation.

While I have set out certain objects, advantages and purposes of my invention in the foregoing general description, other objects, advantages and purposes will be apparent from a consideration of the foregoing disclosure and the accompanying drawings in which,

FIGURE 1 is an isometric view of a preferred embodiment of my clamp;

FIGURE 2 is a front elevation of a preferred embodiment of my clamp;

FIGURE 3 is a side elevation of the embodiment shown in FIGURE 1;

FIGURE 4 is a side elevation of the second embodiment of my invention; and

FIGURE 5 is an isometric view of the embodiment of FIGURE 4.

Referring to the drawings, I have illustrated a neutral wire clamp according to my invention comprising a body portion 10 having two upstanding legs 11 and 12, forming between them a U-shaped opening 13 adapted to receive a main conductor 14. Spaced from the bottom of opening 13 is a passageway 15 parallel to the bottom of opening 13 adapted to receive the end of a ground wire 16. A set screw 17 is threaded in an opening 18 transverse to passage 15 so as to clampingly engage the end of wire 16. An abutment portion 19 is fixed to one side of the body 10 and is separated from the leg 12 by a slot or passage 20. Bolt holes 21 and 22 in legs 12 and 11 respectively are adapted to receive a bolt 23 passing transversely above wire 14. Abutment 19 is designed to engage the head 24 of the bolt 23 so as to prevent it from turning when the nut 25 on the opposite end of the bolt is turned and tightened. The bolt 23 is long enough to pass entirely through a supporting pole 26 and to pass

2

through the legs 11 and 12 and receive a nut 25 on the end. When the nut 25 is tightened, the leg 12 tends to wrap around the conductor 14 grasping it in a clamping arrangement between the legs 11 and 12.

5 In the embodiment shown in FIGURES 4 and 5, I provide a body portion 30 having a pair of legs 31 and 32 forming between them a U-shaped opening 33 adapted to receive a conductor 34. A passage 35 passes through the body 30 parallel to the bottom of the opening 33 and is connected therewith through a slot 36. A set screw 37 clampingly engages a wire 38 in passage 35. An abutment 40 is formed on the leg 32. Openings 41 and 42 in legs 31 and 32 are adapted to receive a bolt 44 corresponding to the bolt 23 of the embodiment shown in FIGURES 1, 2 and 3. The bolt head 45 is adapted to be engaged by the abutment 40 to hold it against turning. When a nut is tightened on the bolt 44 and leg 32 is drawn toward the leg 31 grasping the conductor 34 in a clamping arrangement.

20 A plastic cover 50 having an inner well corresponding in shape to that of the body portion and legs of the clamp is provided to cover the clamp and insulate the junction formed by it. An inner lug 51 on the cover is adapted to be engaged between the legs 11 and 12 or 31 and 32 and the cover slidably to fit over the clamp. The cover will remain in position by reason of its own weight and manner of suspension although frictional engagement may be provided between its sidewall 52 and the edges of the legs 31 and 32. In addition, the remaining conductors 53 and 54 of a three wire system such as "Triplex" will hold the cover tightly in place as they are in turn held away and insulated from the clamp itself.

25 While I have illustrated and described certain preferred embodiments of my invention, it will be understood that this invention may be otherwise embodied within the scope of the following claims.

I claim:

1. An electrical conductor clamp comprising a body portion, a pair of side-by-side legs extending from said body portion forming between them a generally parallel sided U-shaped slot to pass over the body of a conductor, said body portion having a passage spaced from and generally parallel to the bottom of said slot and adapted to receive an end of wire, clamping means in the body adapted to enter the passageway to clampingly engage the wire, a slot in the body portion adjacent the base of one of the legs creating a zone of resilience whereby said one leg may bend towards the other, said legs having openings spaced from the bottom of the slot to receive a clamping bolt, a clamping bolt in said openings and an abutment on the body portion adjacent the opening in one of the legs and engaging the head of the bolt therein.

2. An electrical conductor clamp comprising a body portion, a pair of side-by-side legs on the body portion forming between them a generally parallel sided U-shaped slot to pass over the body of a conductor, said body portion having a passage spaced from and generally parallel to the bottom of said slot and adapted to receive an end of a wire, clamping means in the body adapted to enter the passageway to clampingly engage the wire, a slot in the body portion between the base of the legs and connecting the bottom of the slot and the passageway creating a zone of resilience whereby one of the legs may bend towards the other, said legs having openings spaced from the bottom of the slot to receive a clamping bolt, a clamping bolt in said openings and adapted to pass through a supporting pole whereby to fix said clamp and conductors on said pole, and an abutment on the body portion adjacent the opening in one of the legs and engaging the head of the bolt therein.

3. An electrical conductor clamp comprising a body portion, a pair of side-by-side legs on the body portion

forming between them a generally parallel sided U-shaped slot to pass over the body of a conductor, said body portion having a passage spaced from and generally parallel to the bottom of said slot and adapted to receive an end of a wire, clamping means in the body adapted to enter the passageway to clampingly engage the wire, a slot in the body portion forming an external tongue extending along the base of one of the legs creating a zone of resilience whereby one of the legs may bend towards the other, said legs having openings spaced from the bottom of the slot to receive a clamping bolt, a clamping bolt in said openings, an abutment on the body portion adjacent the opening in one of the legs and engaging the head of the bolt therein.

4. An electrical conductor clamp comprising generally a rectangular body portion, a pair of substantially parallel legs extending from said body portion forming between them a generally parallel sided U-shaped slot to pass over the body of a conductor, said body portion having a passage spaced from and generally parallel to the bottom of said slot adapted to receive an end of a wire, clamping means in the body adapted to enter the passageway to clampingly engage the wire, a slot in the body portion adjacent the base of one of the legs creating a zone of resilience whereby one of the legs may bend

5 towards the other, said legs having openings spaced from the bottom of the slot to receive a clamping bolt, a clamping bolt in said openings, an abutment on the body portion adjacent the opening in one of the legs and engaging the head of the bolt therein, said body portion being rounded from the abutment to form a smooth arcuate surface and cover means engaging the legs and surrounding the bolt head the slot and the arcuate surface.

5. A clamp as claimed in claim 4 wherein the cover 10 is plastic and is provided with a tongue slidably engaging between the legs and covering the clamp in frictional engagement.
